UNITED STATES PATENT OFFICE.

CHARLIE A. SIMONDS, OF BUCHANAN, MICHIGAN.

COMBINED SHOE-HOLDER AND BOX-DRAW.

SPECIFICATION forming part of Letters Patent No. 225,652, dated March 16, 1880.

Application filed January 26, 1880.

To all whom it may concern:

Be it known that I, CHARLIE A. SIMONDS, of Buchanan, in the county of Berrien, and in the State of Michigan, have invented certain new and useful Improvements in Shoe-Holder and Box-Draw Combined; and I do hereby declare that the following is a full, clear, and exact description thereof, reference being had to the accompanying drawings, and to the letters of reference marked thereon, making a part of this specification.

The nature of my invention consists in the construction and arrangement of a device for attaching shoes to boxes, as will be hereinafter more fully set forth.

In order to enable others skilled in the art to which my invention appertains to make and use the same, I will now proceed to describe its construction and operation, referring to the annexed drawings, in which—

Figure 1 is a perspective view, and Fig. 2 a side view, of my invention.

My shoe-fastener is made of a single piece of metal, and is composed of a bar, A, with a hole, a, near each end. Near the upper end is formed a shank or projection, B, terminating in a ring, C, and from the same projects downward a spring-tongue, D.

This device may be made of any suitable kind of metal and more or less ornamented, as desired. It is fastened to a wooden box by means of screws passed through the holes.

When it is to be attached to a paper box a piece of wood must be placed on the inside of the box to form a backing to receive the screws.

The ring C forms a handle for drawing out the box. The shoe to be attached on the outside of the box is pulled up between the tongue D and bar A, the spring of the tongue holding it in place.

Having thus fully described my invention, what I claim as new, and desire to secure by Letters Patent, is—

As a new article of manufacture, a combined shoe-holder and box-draw, consisting of the bar A, ring C, and spring-tongue D, all constructed substantially as and for the purposes herein set forth.

In testimony that I claim the foregoing I have hereunto set my hand this 21st day of January, 1880.

CHARLIE A. SIMONDS.
